UNITED STATES PATENT OFFICE.

FREDRICK W. JOHNSON, OF WASHINGTON, DISTRICT OF COLUMBIA.

DESIGN FOR A WARDROBE-TRUNK.

48,639.

Specification for Design.

Patented Feb. 29, 1916.

Application filed May 1, 1915. Serial No. 25,294. Term of patent 7 years.

To all whom it may concern:

Be it known that I, FREDRICK W. JOHNSON, a citizen of the United States, residing in Washington, District of Columbia, have invented a new and original and ornamental Design for Wardrobe-Trunks, of which the following is a specification, reference being had to the accompanying drawing, forming a part thereof.

The figure is a perspective view showing the trunk open.

I claim:—

The ornamental design for a wardrobe trunk, as shown.

FREDRICK W. JOHNSON.

Copies of this patent may be obtained for five cents each, by addressing the "Commissioner of Patents, Washington, D. C."
